Design for a Cook Stove

4320—Plates of a Cook Stove. —Samuel H. Ransom,
Albany, N. Y.

Des. 2320

Samuel H. Ransom of Albany, N.Y.

Letter Patent No. 93910. Dated May 11, 1866.

Design for the plates of a cook stove.

In Schedule referred to in these letter patent for each part of the same

shall when it may occur

Be it known that I, Samuel H. Ransom, of the
City and County of Albany, in the State of New York, have invented or pro-
duced a new and original design for the plates of a cook stove; and I do
declare that the following is a full and exact description of the same,
reference being made to the accompanying photographs:

A represents the design for front side door;

B " " " for front;

C " " " front door;

DF " " " oven doors;

E " " " end fire door.

Together forming plates for a cook stove "Helping Hand."

Claim as new and desire to secure by letters
of patent. The design for plates of a cook stove as shown and described.
